CLAIM

We claim the ornamental design for a well plate, as shown and described.

DESCRIPTION

FIG. 1 is a top perspective view of a well plate showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The bold dashed broken lines extending across the top surface of the well plate in FIGS. 1 and 6 are surface ornamentation that forms part of the claimed design.

The remaining broken lines depict portions of the well plate that form no part of the claimed design.
